(57) **CLAIM**

The ornamental design for an acoustic effect adder for electronic musical instrument, as shown and described.

DESCRIPTION

FIG. 1 is a perspective view of an acoustic effect adder for electronic musical instrument showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an end view taken along line 8-8 in FIG. 6.

The dashed broken lines illustrate portions of the acoustic effect adder for electronic musical instrument and form no part of the claimed design. The dot-dash broken lines define the bounds of the claimed design and form no part thereof.
